ILLUMINABLE CLOCK SIGN

Wilbur H. Berry, Alliance, Ohio, assignor to The Electric Neon Mfg. Co., Cleveland, Ohio, a corporation of Ohio

Application April 29, 1948, Serial No. 146,027

Term of patent 3½ years

(Cl. D1—12)

To all whom it may concern:

Be it known that I, Wilbur H. Berry, a citizen of the United States, residing at Alliance, county of Stark, and State of Ohio, have invented a new, original, and ornamental Design for an Illuminable Clock Sign, of which the following is a specification, reference being had to the accompanying drawing, forming part thereof.

The figure is a front perspective view of an illuminable clock sign, showing my new design, the opposite side being similar to that shown and the back being plain.

I claim:

The ornamental design for an illuminable clock sign, as shown and described.

WILBUR H. BERRY.
